ATTORNEY..

UNITED STATES PATENT OFFICE.

WILLIAM G. MERRIMAN, OF PITTSBURG, PENNSYLVANIA.

COKE-OVEN DOOR.

SPECIFICATION forming part of Letters Patent No. 268,811, dated December 12, 1882.

Application filed April 14, 1882. (No model.)

To all whom it may concern:

Be it known that I, WILLIAM G. MERRIMAN, of Pittsburgh, in the county of Allegheny, State of Pennsylvania, have invented a new and useful Improvement in Doors for Coke-Ovens; and I do hereby declare that the following is a full, clear, and exact description thereof, reference being had to the accompanying drawings, and to the letters of reference 10 marked thereon.

My invention relates to an improvement in coke-ovens; and it consists of a metal frame having vertical ribs which serve as strengthening-strips and guides for the door, which 15 consists of a metal casing lined with fire-brick. To the upper end of said door are attached links, the upper end of which is pivoted to tangent-formed levers having gear-teeth which mesh into each other, said levers being pivoted to the upper part of said frame, and furnished with weights for the purpose of balancing said door, all of which will hereinafter more fully and at large appear.

To enable others skilled in the art with which 25 my invention is most nearly connected to make and use it, I will proceed to describe its construction and operation.

In the accompanying drawings, which form part of my specification, Figure 1 is a front elevation of a coke-oven furnished with my improvement in doors. Fig. 2 is a vertical section of the front wall of a coke-oven and of my improvement in doors. Fig. 3 is a front view enlarged of my improvement in doors for coke- 35 ovens.

Reference being had to the accompanying drawings, A represents the coke-ovens, which are of the ordinary construction. B represents the frame for the door C, and is provided with ribs D, which serve the purpose of strengthening-strips and guides for the door D, which consists of a cast-iron casing lined

with fire-brick. On the upper end of said casing are lugs e, to which are pivoted links f, which at g are pivoted to tangent-formed levers E, pivoted at h to the upper end of the frame B, said levers being furnished with gear-teeth i, which mesh into each other. On the outer end of levers E is attached a cord or chain, F, to the lower end of which are attached weights 45 G for the purpose of balancing the door C. By this arrangement of the door-frame B, doors C, levers E, and weights G the door C can be manipulated with great ease and facility, and held in any desired position with 50 relation to the doorway of the coke-oven.

In the ordinary construction of coke-ovens they are charged at the top with the coal to be coked, and the doorway or the opening for withdrawing the coke is temporarily closed 55 with brick laid with clay or loam mortar. This laying of the brick at each charging of the oven and tearing them down each time the coke is withdrawn from the oven is attended with much cost, labor, and loss of time, which 60 is entirely avoided with my improvement, it being apparent that the doorway of the oven can be opened and closed by my improved door with ease and facility and without loss of time, and can be adjusted for the purpose 65 of admitting air to the coke-ovens at the pleasure of the operator.

Having thus described my improvement, what I claim is—

In a coke-oven, the combination of the frame 75 B, having ribs or guides D, door C, links f, levers E, having gear-teeth i, meshing into each other, and weights G, all constructed, arranged, and operating substantially as shown and described.

W. G. MERRIMAN.
